US0D1045504S

(12) **United States Design Patent** (10) **Patent No.:** **US D1,045,504 S**
(45) **Date of Patent:** **** Oct. 8, 2024**

(54) **BLENDER CONTAINER**

- (71) Applicant: **SharkNinja Operating LLC**, Needham, MA (US)
(72) Inventor: **Joyce Chien Tu**, Melrose, MA (US)
(73) Assignee: **SharkNinja Operating LLC**, Needham, MA (US)
(***) Term: **15 Years**
(21) Appl. No.: **29/870,362**
(22) Filed: **Jan. 23, 2023**

Related U.S. Application Data

- (62) Division of application No. 29/755,785, filed on Oct. 22, 2020, now Pat. No. Des. 984,210.

Primary Examiner — Andrew Kerr*Assistant Examiner* — Chariton Alexakis*(74) Attorney, Agent, or Firm* — The Webb Law Firm**CLAIM**

The ornamental design for a blender container, as shown and described.

DESCRIPTION

FIG. 1 is a perspective view of a blender container, showing my new design;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof; and,

FIG. 7 is a bottom plan view thereof.

The broken lines in the drawings depict portions of the blender container that form no part of the claimed design.
